UNITED STATES PATENT OFFICE

97,999

DESIGN FOR A TOGGERY RACK

Roy E. Hamilton, Kansas City, Kans.

Application August 12, 1935, Serial No. 58,087

Term of patent 7 years

To all whom it may concern:

Be it known that I, Roy E. Hamilton, a citizen of the United States, residing at Kansas City, in the county of Wyandotte and State of Kansas, have invented a new, original, and ornamental Design for a Toggery Rack, of which the following is a specification, reference being had to the accompanying drawing, forming a part thereof.

Fig. 1 is a perspective view of a toggery rack showing my design.

Fig. 2 is a front elevational view of the toggery rack.

Fig. 3 is an end elevational view.

Fig. 4 is a top plan view.

I claim:

The ornamental design for a toggery rack as shown.

ROY E. HAMILTON.
